UNITED STATES PATENT OFFICE

2,446,633

CAN OPENER

James Harvey Chandler, Oak Park, and Myron Jackson Zimmer, Wooddale, Ill., assignors to Ekco Products Company, Chicago, Ill., a corporation of Illinois

Application April 9, 1945, Serial No. 587,364

5 Claims. (Cl. 30—9)

1

This invention relates to can openers, and its general object is to provide a wall type can opener including wall fastening means for accommodating the placement of the device in selected angular positions relative to its support.

It is also an object of this invention to provide a can opener of this type, embodying features of construction, and design which increase its efficiency in service and operation.

This invention also consists in certain other features of construction, and in the combination and arrangement of the several parts, to be hereinafter more fully described, illustrated in the accompanying drawings, and specifically pointed out in the appended claims.

Fig. 1 is a side elevation of a can opener, and mounting bracket therefor, constructed in accordance with this invention and shown in the position in which it is ready for operation.

Fig. 2 is a plan view thereof in the last named position.

Fig. 3 is an end view thereof in the same position.

Fig. 4 is an end view thereof in the position in which it is in operation for removing the top of a can.

Fig. 5 is a collective view, in side elevation, with a part in fragmentary side elevation, showing the relationship of the can opener frame and the wall support, before the frame is mounted on the support.

Fig. 6 is a bottom plan view of the parts shown in Fig. 5, when the frame is mounted on the support.

Fig. 7 is a detail front view partly in vertical section, taken on line 7—7 of Fig. 6.

Fig. 8 is a detail front view of the wall plate shown as the most leftward part of the wall support in Fig. 5.

Reference being had more particularly to the accompanying drawings, numeral 10 indicates the frame or main supporting member of the device forming the subject of this invention, and is adapted to be attached to a wall or similar vertical surface. The frame 10 is of elongated channel-shaped construction, and is preferably formed of suitable light weight metal, as by die-casting. When attached to a wall, the frame 10 presents a horizontal top face 11, with side walls 12 extending downwardly from the opposite longitudinal edges of the top face. One end of the frame 10 presents a flat face 13 for abutment with a conforming surface of a wall bracket, referred to more particularly hereinafter. The opposite end of the frame 10 is curved outwardly and downwardly

2

coincident with the outer surface of a cylindrical boss 14 having its axis at right angles to the longitudinal axis of the frame 10.

A bore extending axially through the boss 14 from opposite faces 12 of the frame 10 provides a bearing for a rotatable shaft 15 having threaded ends 16 and 17 protruding from the axial limits of the bore. The threaded end 16 of the shaft 15 is fitted with a traction wheel 18 for rotation in a plane parallel to the nearest face 12 of the frame 10. A washer 19 may be interposed between the inner face of the traction wheel and the face of the frame to provide a suitable wear-resistant bearing for the inner face of the wheel 18. The threaded end 17 of the shaft 15 is fitted with a handle crank 20 through which the shaft 15 may be operated to rotate the traction wheel.

A cylindrical spacing element 21 bridging the space between the side members 12 of the frame 10 in inwardly spaced parallel relation to the boss 14 is also recessed to provide a bearing for a shaft 22 having ends 23 projecting axially therefrom.

The reference numeral 25 denotes a plate 25 adapted to be mounted on the frame 10 for swinging movement toward and away from the top face of the frame by means of ears 26 formed integrally with and extending downwardly from transversely aligned edge portions of the plate 25 and attached to the ends 23 of the shaft 22. The frame 10 is preferably recessed as at 27 so as to maintain the ear 26, and the portion of the shaft 22 within planes substantially flush with the outer surface of the sides of the frame 10 and yet provide ample clearance for movement of the ears.

The swinging end of the plate 25 is urged to a position upwardly away from the top of the frame 10 by means of a coil spring 30 having one end seated in an upwardly opening depression 31 formed in the top of the frame 10 and having its other end in engagement with the lower face of the plate 25. An opening 32 formed in the plate 25 is adapted to have its edges clear a lug or post 33 formed integrally with and projecting upwardly from the top of the frame 10 in the path of the plate 25.

Reference number 34 designates a lever mounted for swinging movement on an axis parallel to the axis of movement of the plate 25 by means of a pivot 35 extending from opposite sides of the portion of the lug 33 disposed above the plate 25 to which forked ends 36 of the lever 34 are suitably fastened. Cam surfaces 37 on the ends 36 are adapted to bear against the upper surface of the plate 25 to depress the latter against resist-

ance of the spring 30 when the lever 34 moved to upright position as in Fig. 4, and to provide clearance for movement of the plate 25 from said depressed position to an elevated position under power exerted by the spring 30 when the lever is moved inwardly toward a recumbent position wherein the free end of the lever 34 rests against the top 11 of the frame 10, as in Figs. 1 and 3.

Extending upwardly from one edge of the plate 25 in overhanging relation to the traction wheel 18 is an inverted U-shaped member providing arms 38 and 39, presenting spaced parallel inner faces in downwardly and inwardly inclined planes. A cutting member in the form of a disc 40 having a peripheral cutting edge 41 and a hub portion 42 is rotatably mounted on a shaft 43 interposed between and arranged at right angles to said inner faces of the arms 38 and 39. Movement of the plate 25 from a raised position to a depressed position under control of the operating lever 34, as described hereinabove, will accordingly carry the disc cutter 40 in a downward path toward a position in which the lower portion of the cutting edge will overlap and pass into close proximity to the outer face of the traction wheel 18.

Rotation of the shaft by means of the handle and thus causing the traction wheel 18 to turn with the bead of a can 45 gripped between the cutter and the traction wheel 18 causes the can to turn relative to the frame 10 and the head 44 of the can to be completely severed from the side wall thereof. A projection 46 extending downwardly and outwardly from the lower limits of the frame 10 in underlying relation to the traction wheel presents a bearing edge 47 against which the side wall 48 of the can may ride and be maintained in position to avoid spilling of the can contents during the can opening operation. A flange 49 extending laterally from the plate 25 presents an under-surface against which the bead of the can may ride to avoid tipping about an axis parallel to the axis of the traction wheel.

Fig. 5 illustrates a form of bracket through which the frame 10 may be mounted in a horizontal position on a wall or other supporting surface. This bracket includes a base plate 50 fastened as at 51, by screws, to the surface of a wall 52, and a cover member 53. A peripheral flange 54 on the member 53 extending angularly therefrom in the direction of the base plate 50 is adapted to fit and overlap the edge of the base plate 50 so that the latter is wholly concealed by the member 53. A boss 55 in the plate 50 is threaded to receive a fastening screw 57 which extends through a counterbored opening 56 in the member 53, whereby the latter is rigidly secured to the base plate 50.

The cover member 53 is preferably formed to provide a horizontal supporting ledge 60 in downwardly offset relation to a top surface 61 in the direction of the wall to which it is attached, for supporting the frame 10 in extended position with its upper surface flush with said top surface 61. A back wall 62 extending upwardly from the inner limits of the ledge 60 is arranged to make a close joint with the end face 13 of the frame 10 when the latter is in mounted position on the ledge 60. The side portions of the member 53 which extend downwardly from the edge of the top 61 are also preferably arranged to form a smooth continuation of the surfaces of the sides 12 of the frame 10.

Rising centrally from the ledge 60 is a boss 64 forming a raised rim for a recess 65 of sufficient depth to intersect the counterbore 56 in the mem-

ber 53, which provides a seat for a post or spindle 66 extending below the lower edges of the sides 12 of the frame 10. When the spindle 66 is seated in the well 65 the flat end face 13 of the frame 10 engages the back wall 62 of the member 53, and the lower edges of the sides 12 of the frame rest on the ledge 60. At the same time, the spindle 66 conceals the head of the screw 57 at the inner limits of the counterbore 56. A shoulder 67 created by a downwardly and upwardly offset flange 68 at the lower edge of each of the sides 12 of the frame 10 is also adapted to engage the forward edge of the ledge 60 so as to more securely hold the frame 10 against movement to the member 53 about spindle 66 as an axis.

The flange 68 may also be longitudinally tapered to provide a pleasing continuation of the exposed side edges of the ledge 60 as shown in Fig. 1.

By lifting the frame 10 sufficiently to raise the lower edge of the frame above the upper limits of the back wall 62, the frame 10 may be swung to a position in either direction laterally of its forwardly extending position through an arc of 90 degrees and thereupon lowered to place the end face 12 against the back wall 62, whereupon the shoulders 67 engage a side edge of the ledge 60 and the frame 10 is again locked against turning movement about the spindle 66 as an axis.

In operation the cam lever 34 is moved from a recumbent position along the top of the frame member 11 to an upright position as shown in Fig. 4 whereupon the cutting member 40 is lowered to a depth sufficient to penetrate the top 44 of a can 45 while the bead 49 of the can is confined between the upper edge of the traction wheel 18 and the underside of the flange 49. With the operating parts in this position, the side of the can 48 bears against the edge of the projection 46. The handle 20 is then engaged by the operator and actuated to rotate the shaft 15 and the traction wheel 18. Rotation of the traction wheel 18 causes the edge 41 of the cutting member 40 to turn the can 45 and as this is being done the cutting edge 41 of the cutting member 40 causes the head 44 of the can to be sheared from the side wall 48. At the same time the curved shoulder between the hub 42 and the cutting edge 41 of the cutting member acts upon the residuary portion of the head 44 of the can still attached to the side wall 48 to be bent downwardly in a position resting flush against the inner face of the can wall. When the head 44 has been completely severed the can bead is still firmly secured between the traction wall 18 and the cutting member 40. When it is desired to remove the can therefrom the cam lever 34 is swung from an upright position to the recumbent position shown in Fig. 1 whereupon the plate 25 is raised by the pressure of the spring 30 to lift the cutting member 40 a distance sufficiently above the traction wheel 18 to permit easy withdrawal of the can 45.

It will be recognized from the foregoing description that the bore which extends through the boss 14 from opposite faces 12 of the frame 10 provides a bearing of a length exceeding the dimension of the frame measured in a vertical plane through the bore whereby the shaft 15 carrying the traction wheel 18 is accurately and securely supported to resist the bending forces applied on the shaft 15 through the traction wheel 18 during operation of the can opener. It will also be understood that the particular manner in which the cam lever 34 is swung between

operative and idle positions with respect to the longitudinal axis of the frame member 11 is especially advantageous from the standpoint of confining the operating mechanism in a restricted area compatible with the disposal of the frame 11 with its long axis parallel to the wall 52 on which the bracket members 50 and 53 are secured.

What is claimed is:

1. In a can opener, the combination with an elongated frame adapted to be attached at one end thereof to a fixed support so as to dispose its opposite end in forwardly projecting relation to the attached end and provided with a bearing at the forward end thereof in transverse relation to the longitudinal axis of said frame, a shaft mounted in said bearing having its ends protruding from the ends of said bearing, a can bead engaging traction wheel fixed to one end of said shaft, means fixed to the opposite end of said shaft for driving the shaft and rotating said traction wheel, a plate positioned above and pivotally secured to the frame for swinging movement about an axis parallel to said bearing, means projecting from the outer swinging end of said plate presenting a pair of opposed legs spaced apart in a direction laterally of the path of movement of said plate in over-hanging relation to said traction wheel, a cutting wheel supported between said legs for rotation about a downwardly inclined axis and movable toward and away from a position in closely overlapping relation to the said traction wheel during swinging movement of said plate, a spring interposed between said plate and frame acting to resist swinging movement of the plate in the direction of a position wherein the cutting wheel overlaps said traction wheel, and means for moving said plate in opposition to said spring including a cam lever mounted on said frame for movement in a path in alignment with the longitudinal axis of the frame.

2. In a can opener, the combination with an elongated frame adapted to be attached at one end thereof to a fixed support so as to dispose its opposite end in forwardly projecting relation to the attached end and provided with a bearing at the forward end thereof in transverse relation to the longitudinal axis of said frame and of a length at least equal to the dimension of the frame measured on a vertical plane through said bearing, a shaft mounted in said bearing having its ends protruding from the ends of said bearing, a can bead engaging traction wheel fixed to one end of said shaft, means fixed to the opposite end of said shaft for driving the shaft and rotating said traction wheel, a plate positioned above and pivotally secured to the frame for swinging movement about an axis parallel to said bearing, means projecting from the outer swinging end of said plate presenting a pair of opposed legs spaced apart in a direction laterally of the path of movement of said plate in over-hanging relation to said traction wheel, a cutting wheel supported between said legs for rotation about a downwardly inclined axis and movable toward and away from a position in closely overlapping relation to the said traction wheel during swinging movement of said plate, a spring interposed between said plate and frame acting to resist swinging movement of the plate in the direction of a position wherein the cutting wheel overlaps said traction wheel, and means for moving said plate in opposition to said spring including a cam lever mounted on said frame for movement in a path in alignment with the longitudinal axis of the frame.

in alignment with the longitudinal axis of the frame.

3. In a can opener as claimed in claim 1 where-in said cam lever is movable from a recumbent position above the frame to an upright position.

4. In a can opener, the combination with an elongated frame adapted to be attached at one end thereof to a fixed support so as to dispose its opposite end in forwardly projecting relation to the attached end and provided with a bearing at the forward end thereof in transverse relation to the longitudinal axis of said frame, a shaft mounted in said bearing having its ends protruding from the ends of said bearing, a can bead engaging traction wheel fixed to one end of said shaft, means fixed to the opposite end of said shaft for driving the shaft and rotating said traction wheel, a plate positioned opposite the top face of said frame, a pair of ears formed integrally with and extending downwardly from transversely aligned edge portions of the plate, transversely aligned recesses formed in the side walls of said frame and intersecting the top face of the frame in which said ears of the plate are received with the outer faces of the ears substantially flush with the outer surface of the side walls of the frame, means for supporting said ears in said recesses for swinging movement about an axis parallel to said bearing, means projecting from the outer swinging end of said plate presenting a pair of opposed legs spaced apart in a direction laterally of the path of movement of said plate in over-hanging relation to said traction wheel, a cutting wheel supported between said legs for rotation about a downwardly inclined axis and movable toward and away from a position in closely overlapping relation to the said traction wheel during swinging movement of said plate, a spring interposed between said plate and frame acting to resist swinging movement of the plate in the direction of a position wherein the cutting wheel overlaps said traction wheel, and means for moving said plate in opposition to said spring including a cam lever mounted on said frame for movement in a path in alignment with the longitudinal axis of the frame.

5. In a can opener, the combination with an elongated frame adapted to be attached at one end thereof to a fixed support so as to dispose its opposite end in forwardly projecting relation to the attached end and provided with a bearing at the forward end thereof in transverse relation to the longitudinal axis of said frame, a shaft mounted in said bearing having its ends protruding from the ends of said bearing, a can bead engaging traction wheel fixed to one end of said shaft, means fixed to the opposite end of said shaft for driving the shaft and rotating said traction wheel, a plate positioned above and pivotally secured to the frame for swinging movement about an axis parallel to said bearing, means projecting from the outer swinging end of said plate presenting a pair of opposed legs spaced apart in a direction laterally of the path of movement of said plate in over-hanging relation to said traction wheel, a cutting wheel supported between said legs for rotation about a downwardly inclined axis and movable toward and away from a position in closely overlapping relation to the said traction wheel during swinging movement of said plate, an upwardly opening depression formed in the top of the frame, a spring seated in said depression and acting against the under-side of said plate to resist swinging movement of

the plate in the direction of a position wherein the cutting wheel overlaps said traction wheel, and means for moving said plate in opposition to said spring including a cam lever mounted on said frame for movement in a path in alignment with the longitudinal axis of the frame.
